F. L. McGARY

BOX STRAP SEAL

Filed Sept. 6, 1923

Patented Dec. 2, 1924.

UNITED STATES PATENT OFFICE.

FRANCIS L. McGARY, OF HARDINSBURG, KENTUCKY.

BOX STRAP SEAL.

Application filed September 6, 1923. Serial No. 661,325.

To all whom it may concern:

Be it known that I, FRANCIS L. McGARY, a citizen of the United States, and a resident of Hardinsburg, in the county of Breckinridge and State of Kentucky, have invented certain new and useful Improvements in Box Strap Seals, of which the following is a specification.

This invention relates to box strap seals or 10 seals for the ends of barrel hoops and has for its object the provision of a device which may be readily applied to the overlapped ends of metal straps and which is provided with slots adapted to neatly receive portions 15 of the deformed edges of the overlapped straps for locking the overlapped ends of the straps together.

A further object of the invention is the provision of a device adapted to receive the 20 overlapped ends of metal straps with portions of the overlapped ends being deformed simultaneously with the edges of the device whereby straps are interlocked together and interlocked with the device.

This invention will be best understood from a consideration of the following detailed description in view of the accompanying drawing forming a part of the specification; nevertheless it is to be understood 25 that the invention is not confined to the disclosure, being susceptible of such changes and modifications which shall define no material departure from the salient features of the invention as expressed in the appended claims.

In the drawings:

Figure 1 is a view in perspective of the pair of overlapped straps locked together by my improved method.

Figure 2 is a view in perspective of the metal sealing device constructed according to my invention.

Figure 3 is a transverse section taken along the line 3—3 of Figure 1.

Figure 4 is a view in perspective of a modified form of the locking device.

Figure 5 is a transverse section taken along the line 5—5 of Figure 4.

Figure 6 is a view in perspective of the form of metal sleeve shown in Figure 4.

Referring more particularly to the drawings 50 1 and 2 designate metal straps having their ends in overlapped relation and received between the base plate 3 and the inverted spaced flanges 4 of a metal sleeve 5. While I have shown the free edges of the

inturned flanges 4 spaced apart they may be in engagement with each other without affecting the scope of the invention.

The inner side edges 6 of the flanges 4 are 60 spaced from each other while portions of the base 3 defined by the inner edges 6 are cut away as shown at 7 to form slots and adapted to receive the deformed peripheral edges 8 of the overlapping straps 1 and 2 65 when some suitable instrument has been applied to the edges exposed to the slots 7. The tongues 8 of the straps 1 and 2 are bent sufficiently upward to engage the edges 6 of the flanges 4 and the side edges 9 of the slots 70 7 and thereby not only lock the sleeve 5 to the metal straps but rigidly lock the ends of the straps together and prevent separation of the same.

The metal sleeve 5 is formed from a 75 rectangular blank by cutting out portions to form the slots 7 and the spaced side edges 6 of the flanges 4 when the flanges 4 are bent in spaced relation beneath the base 3 80 of the sleeve 5.

By cutting away the member 5 to form the slots 7 and the spaced flanges 4 the base member 3 of the sleeve is bent at that portion between the slot 7 and conforms to the shape of an article to which straps 1 and 85 2 have been applied and secured.

Referring to Figures 4 to 6 inclusive, it will be seen that a similar result is obtained by forming a sleeve 5^a but omitting the slots 7 and the spaced side edges 6 of the 90 flanges 4. The flanges 4^a of the sleeve 5^a extend the full length of the sleeve but due to the lack of the slots 7 the base 3^a will not readily conform to the shape of the container to which the straps are applied and 95 this form of sleeve is better adapted for containers which have flat sides.

The same form of tool which has been applied in shearing the side edges of the straps 1 and 2 to form the tongues 8 is 10 likewise applied to the overlapping straps 1^a and 2^a and likewise to the embracing sleeve 3^a. The peripheral edges of the sleeve 5^a and the straps 1^a and 2^a are sheared and bent upwardly as shown in Figures 4 and 5^a thereby causing the edges of the tongues 9 embracing the raised portion 10 of the sleeve 5^a to secure the sleeve 5^a in locked relation with the ends of the straps 1^a and 2^a thereby locking the ends of the straps together.

The shearing of the lateral edges of the straps is performed in an upward manner

and the lips on the straps thus formed between the sheared portions are bodily raised either through the slots in the sleeves, shown in Figures 1 to 3, or the lips and the adjacent metal of the sleeves shown in Figures 4 to 6 inclusive are bodily raised simultaneously.

What I claim is:

1. A strap seal comprising overlapped strap ends and a sleeve embracing said ends, said sleeve being provided with transverse slots extending inwardly of the opposite longitudinal edges of the sleeve, portions of the longitudinal edges of the strap ends where embraced by the sleeve being sheared from below and transversely of the sleeve to form lips, said lips being elevated above the plane of the sleeve and having their side edges in engagement with the side edges of

the slot whereby the strap ends of the sleeve are locked rigidly together.

2. A strap seal comprising overlapped strap ends and a sleeve embracing said ends, said sleeve being sheared at its longitudinal edges to provide transverse slots extending inwardly of the opposite longitudinal edges of the sleeve, the metal of the sleeve where sheared upon the slot being forced upward and projecting above the plane of the sleeve portions of the longitudinal edges of the strap ends where embraced by the sleeve being sheared from below and transversely of the sleeve to form lips, said lips having their side edges in engagement with the side edges of the slots in the sleeves, the lips being embraced by the upturned sheared portions of the sleeve.

FRANCIS L. McGARY.
